(57) **CLAIM**

The ornamental design for a handheld garment steamer, as shown and described.

DESCRIPTION

FIG. 1 is a front right side perspective view of an ornamental design for a handheld garment steamer according to the present invention;

FIG. 2 is rear left side perspective view of the handheld garment steamer of FIG. 1;

FIG. 3 is a front elevational view of the handheld garment steamer of FIG. 1;

FIG. 4 is a rear elevational view of the handheld garment steamer of FIG. 1;

FIG. 5 is a right side elevational view of the handheld garment steamer of FIG. 1, and the view of the handheld garment steamer that is rotated 180 degrees from FIG. 5 is a mirror image of FIG. 5;

FIG. 6 is a top plan view of the handheld garment steamer of FIG. 1; and,

FIG. 7 is a bottom plan view of the handheld garment steamer of FIG. 1.

The broken line showing of FIGS. 1-7 is for the purpose of illustrating environmental structure and forms no part of the claimed design.

1 Claim, 7 Drawing Sheets
